UNITED STATES PATENT OFFICE.

HARVEY T. WHITE, OF WASHINGTON, DISTRICT OF COLUMBIA.

NON-REFILLABLE BOTTLE.

SPECIFICATION forming part of Letters Patent No. 659,272, dated October 9, 1900.

Application filed February 5, 1900. Serial No. 4,008. (No model.)

To all whom it may concern:

Be it known that I, HARVEY T. WHITE, a citizen of the United States, formerly of New York, (Brooklyn,) Kings county, New York, 5 but now residing at Washington, in the District of Columbia, have invented certain new and useful Improvements in Non-Refillable Bottles, of which the following is a specification.

10 My invention relates to non-refillable bottles and to those in which a valve fitted to a seat to close the latter as the bottle is tilted; and my invention consists in so constructing the parts that the valve is drawn back by the 15 lever action of its stem upon a bearing of the bottle, as fully set forth hereinafter and as shown in the accompanying drawings, in which—

20 Figures 1 and 2 are sectional views of the top of the bottle, showing the valve in different positions. Fig. 3 is an end view, and Figs. 4 and 5 are detail views of modified forms of the valve.

25 The body A, of any suitable form, is provided with a cylindrical neck B, within which is inserted after filling the bottle a block C, having tortuous passages x and so secured in any suitable manner that after insertion it cannot be removed without fracturing.

30 As shown, the block C has a projection extending from its bottom wall only, which is provided with integral ribs at right angles to each other and has an annular recess receiving a packing a, which may be of cork and which as the block is inserted is brought opposite an annular recess y in the interior of the neck, into which it expands, thus holding the block in place.

35 To prevent the cork from being cut by inserting a blade between the block and the inside of the neck, I provide the latter with an inner rib c, having beveled upper and lower faces, which permit the cork to pass readily over the rib, the latter being so situated that 40 when the block is in place it will occupy a position above the space between the side of the block and the neck, and thus interfere with the introduction of a cutting-blade. Instead of cork any suitable packing or material saturated with cement, or cement itself, 45 may be used.

To prevent the passage of a wire through

the channels x and downward to disturb the valve, hereinafter described, the lower ends of the channels x are preferably inclined upward, as shown in Fig. 1, and the sides of the block may be thickened above the channels, so as to present shoulders v, that will interfere with the passage of wires downward into the ends of the channels. 55

The valve D has a head f, spherical in form, and a pendent stem g, the lower end of which is made as thick as possible without interfering with the passage of the stem into the body of the bottle, within which it hangs, while the 60 head rests upon the seat w, formed at the junction of the neck and the body of the bottle. This permits the stem to swing to the desired extent toward the sides of the bottle to lock the head of the valve in place, as shown 65 in Fig. 1. If the bottle is tilted to a sufficient extent, as shown in Fig. 1, the valve will slip forward until its edge strikes the bottom of the plug C, and the liquid will find a ready outlet. Heretofore in articles of this character the stems of the valves have been substantially cylindrical, and as a consequence 70 it is possible to bring the parts into the position shown in Fig. 2 and then by gradually tilting back the body toward an upright position to permit liquid to pass into the same 75 without disturbing the position of the valve. 80

To avoid this result, I provide the stem g of the valve with an inclined bearing-face u and also round the bottle at the junction of 85 the neck and body and just below the seat to form an annular inclined face s, so that on any attempt to carry the bottle from the position shown in Fig. 1 toward a more horizontal position the weight of the end of the 90 stem in conjunction with the inclined faces on the stem and bottle will result in drawing back the head and carrying the parts to the position shown in Fig. 2.

While I have shown in Figs. 1 and 2 one 95 form of stem and arrangement of inclined face u, the form may be varied in different ways—as, for instance, in Figs. 4 and 5—the bearing-face s of the bottle being in each case so shaped as to coact with that upon the stem 100 to insure the head being drawn back by the weight of the stem when the bottle is carried from its inclined position in discharging toward a horizontal position.

As shown, the face *s* is extended to fit the entire part of the stem below the head, so that in the position, Fig. 2, the valve cannot slip or be drawn forward.

5 Without limiting myself to the use of a plug of any suitable form or to the precise form of valve herein set forth, I claim as my invention—

1. The combination of the bottle, its neck 10 and valve, a cup-shaped plug *C* having tortuous passages and a projection extending from its bottom wall only, and formed with integral right-angled ribs, a packing adapted to openings in the plug and neck, and a rib *c* with inclined faces arranged within the neck 15 in a position above the upper end of the plug when the latter is in place, substantially as and for the purpose set forth.

2. The combination of the bottle, a cup- 20 shaped plug *C* having tortuous passages and

a projection extending from its bottom wall only, and formed with integral right-angled ribs, a packing adapted to openings in the plug and neck, and a rib *c* with inclined faces arranged within the neck in a position above 25 the upper end of the plug when the latter is in place, a valve-seat at the junction of the body and neck and a valve having a spherical head adapted to said seat, a weighted stem and inclined face upon said stem and a 30 bearing-face upon the bottle below the seat, substantially as and for the purpose set forth.

In testimony whereof I have signed my name to this specification in the presence of two subscribing witnesses.

HARVEY T. WHITE.
